FIRE POT FOR FUEL OIL BURNERS

Filed Jan. 15, 1927

INVENTOR
WILLIAM J. PRESS.
By *Arnold D. Kennedy*,
ATTORNEY.

UNITED STATES PATENT OFFICE.

WILLIAM J. PRESS, OF OTTAWA, ONTARIO, CANADA.

FIRE POT FOR FUEL-OIL BURNERS.

Application filed January 15, 1927. Serial No. 161,351.

This invention relates to improvements in a fuel oil burner, appertaining particularly to the fire pot thereof that is novel in design and embodies a baffle plate and a supporting standard that contribute to its decidedly augmented efficiency, the same being readily adapted for installation in domestic furnaces such as are commonly used for burning coal and analogous fuels.

10 An object is to provide a fire pot with an air inlet in the bottom into which the flame is discharged tangentially at the bottom, at a high velocity and whirls circumferentially up the pot to flow outwards over the walls 15 in one even unbroken flame.

Another object is to provide a fire pot of the character described for a fuel oil burner that is open at the top and supports a baffle plate thereabove on a central coaxial standard so that the continuity of the flooding 20 whirling flame is uninterrupted.

Another object is the provision of a fire pot having a baffle plate rotatably supported in this way that is concavo-convex and invertable thereby enabling the adjustment of the height of the open ring between the top of the fire pot wall and the baffle from the latter of which a removable finger depends, near the periphery, overhanging the 30 upper rim of the pot and intended to break the flooding flame opposite the door of the furnace.

Another object is to provide a fire pot for a fuel oil burner that is economical, safe and 35 free from ash, smoke, dirt or odor, giving as nearly as possible complete combustion.

A still further object is to provide an improved fire pot for a fuel oil burner as described, that is characterized by structural 40 simplicity, compactness and low cost of manufacture and comprising parts, few in number and that are readily assembled or replaced, and is thereby rendered commercially desirable.

45 To the accomplishment of these and related objects that may appear, the invention resides in the construction, combination and arrangement of parts as shall be hereinafter more fully described, illustrated in the accompanying drawings and pointed out in the 50 claims hereunto appended.

The invention can be most clearly described; and will be best understood when reference is had to the accompanying drawings, forming a part of this disclosure and

wherein like characters indicate like parts throughout the several views.

In the drawings:

Fig. 1 is a plan view of the assembled 60 fire pot;

Fig. 2 is a vertical section on line 2—2 of Fig. 1; and

Fig. 3 is a perspective detail of the finger that depends from the baffle plate.

The details of construction of this embodiment will now be set forth. The fire pot proper comprises a two piece container; a round bowl 4 with a central opening 5 in the base 6, a flanged inlet opening 7 entering the bowl tangentially near the bottom 70 and an open top 8, the upper rim of the circular wall 9 having a central groove 10, and an annular ring 11 that rests on the wall 9, providing an extension thereof, having a tongue 12 on the lower rim adapted to seat 75 in the groove 10; the purpose of this separable construction being to facilitate installation and replacement.

A hollow standard 13 with an exterior flange 14 spaced in from the lower end rests 80 in the opening 5 in the fire pot bowl 4, the flange 14 forming a supporting shoulder while the end of the standard 13 below the flange continues through the said opening to terminate flush with the exterior of the 85 fire pot bowl. Air is admitted to the bowl from the hollow standard 13 by air vents 15 that extend radially through the wall of the standard just above the flange 14. The upper end of the standard is very 90 similarly formed having an exterior flange 16 spaced from the end to provide a supporting shoulder on the upper side for a purpose to be later explained, but rounded on the under side as at 17 to deflect the products of combustion outwardly and terminally interiorly threaded as at 18 to receive the axially perforated plug 19 that partially 95 closes the top of the standard thus allowing 100 of the passage of sufficient air, admitted through the lower end of the pipe, to prevent undue overheating of the standard and yet partially blocking the top end so that some of the current of air must find outlet 105 through the air vents 15. A concavo-convex 110 baffle plate 20, equal in diameter to the bowl, rests on the shoulder 16, having a central bore 21 to receive the end of the standard 13 above the flange. This disk-like baffle 20 is loosely mounted on its supporting stand-

ard being rotatable and invertable so that its periphery may curve upwardly from its centre or droop toward the upper rim of the built-up fire pot. To support a deflector 22 formed as a flat or slightly arcuate depending finger with a threaded stem 23 continuing upwardly from centrally of its top, the baffle 20 has a perforation 24, paralleling the central bore 21, near its circumference through which this stem is adapted to pass and fasten with a co-operating nut 25.

It will of course be obvious that if desired the wall of the pot could comprise three instead of two sections, or the central standard could be cast integral with the bowl and have its upper end partially closed or the depending finger might be cast with the baffle if the latter was not necessarily invertable.

The purpose and structure of the device having been thus described in detail, there now follows a brief reference to its use and modus operandi: When installed and placed in operation, a flame of high velocity enters the pot through the tangential inlet 7 and whirls up the pot. Auxiliary air enters the fire pot through the vents 15 from the standard 13, open through the bottom, due to induction and a secondary current of air passes upwards and out through the bore in the plug 19. The whirling flame, deflected outwards by the centrifugal force of its own action, and by the curved under side 17 of the standard's flange 16 and the baffle 20 floods out over the rim of the fire pot in an even unbroken flame except for the insertion of the deflector finger 22 that obstructs its course. This hanging finger is adjusted to interrupt the flame opposite the door of the furnace, being spaced circumferentially therefrom into the path of the circling fire. In this way no obstacle breaks the flame except to protect the door opening so that the maximum of efficiency results from the combustion and further the force of the blast is distributed most evenly about the circumference of the furnace thus lengthening its life of usefulness by preventing undue concentration of the flame in limited areas of the wall that must eventually burn through.

From the foregoing description taken in connection with the accompanying drawings, it will be manifest that a fire pot for a fuel oil burner is provided which will fulfill all the necessary requirements of such a device, but as many changes could be made in the above description and many apparently widely different embodiments of my invention constructed within the scope of the appended claims without departing from the spirit or scope thereof, it is intended that all matters contained in the said accompanying specification and drawings shall be interpreted as illustrative and not in a limited sense.

What I claim as new and desire to secure by Letters Patent is:—

1. A fire pot comprising a vertical bowl having a central bore in the base thereof and a flanged oil feed opening entering tangentially through the side wall thereof; a hollow standard exteriorly flanged at both ends; and a centrally perforated baffle plate, said standard resting in said central bore on the shoulder afforded by one flange and supporting said centrally perforated baffle with the other.

2. A fire pot for a fuel oil burner comprising a bowl having a tangential oil feed opening; a hollow standard within said bowl radially and upwardly perforated near its base; said hollow standard being interiorly threaded at the top and having a flange near its upper end, said flange being curved on its under side; a plug with an axial bore threaded in the top of said standard and a baffle supported on the shoulder afforded by said flange.

3. A fire pot for a fuel oil burner comprising a bowl; a standard therein having an exterior flange near its upper end; a baffle plate centrally perforated to receive said standard and adapted to be supported on said flange; said baffle plate having an aperture near the periphery thereof; a deflector having a threaded stem on its upper end adapted to project through said aperture; and a co-operating nut adapted to engage said stem after it has passed through said baffle plate.

4. A fire pot for a fuel oil burner comprising a bowl having a central bore in the base thereof and a flanged opening entering tangentially through the side wall thereof near the bottom; an annular band providing an extension for the wall of said bowl resting on the rim thereof; a hollow standard resting in said central bore; said hollow standard being exteriorly flanged and threaded near both ends; said hollow standard having radial perforations just above the lower flange, the upper flange being curved on its under side; a plug with an axial bore threaded in the top of said standard; a rotatable and invertable concavo-convex baffle centrally perforated to receive said standard supported on the upper flange thereof; said baffle having an aperture near the periphery whose axis parallels the axis of said central perforation; and a deflector removably carried by said baffle having a threaded stem adapted to pass through said aperture and be secured by a co-operating nut, substantially as described.

5. A fire pot including a bowl having a flanged tangential oil feed opening in its side wall; a central standard within said bowl; a baffle supported thereby; and a depending deflector finger carried by said baffle at the outer edge thereof.

6. A fire pot including a vertical bowl having a flanged tangential oil feed opening; a central standard supported within said bowl; a baffle mounted thereon; and a depending deflector finger carried by said baffle at the outer edge thereof.
7. A fire pot including a vertical bowl having a central bore in the base thereof; said bowl also having a flanged tangential opening in its side wall; a hollow standard directed upwardly therefrom and having air vents extending radially and upwardly therethrough; a baffle supported on the upper end of said standard; and a depending deflector finger carried by said baffle at the outer edge thereof.
8. A fire pot including a vertical bowl having a tangential oil feed opening in its side wall above the bottom of the bowl; a

central standard supported in said bowl; an invertable concavo-convex baffle mounted on said standard; and a depending deflector finger carried by said baffle at the outer edge thereof.

9. A fire pot for a fuel burner comprising, 25 a bowl; means for introducing fuel into the bowl; a standard in the bowl; a substantially horizontal baffle plate supported on the standard and over the bowl, for laterally deflecting flame outwardly from the bowl; and 30 a wide finger depending from the outer edge of the baffle plate and disposed across the path of a portion of the flame for interrupting that portion of the flame.

In testimony whereof I hereunto affix my 35 signature.

WILLIAM J. PRESS.
